UNITED STATES PATENT OFFICE.

HENRY T. SCOTT, OF WICHITA FALLS, TEXAS.

PUMPING-JACK.

1,384,638.

Specification of Letters Patent. Patented July 12, 1921.

Application filed August 18, 1919. Serial No. 318,377.

To all whom it may concern:

Be it known that I, HENRY T. SCOTT, a citizen of the United States, residing at Wichita Falls, in the county of Wichita and State of Texas, have invented new and useful Improvements in Pumping-Jacks, of which the following is a specification.

This invention has reference to an improved pumping jack.

10 The object of the invention is to provide means on the walking beam of a jack for equalizing the dead weight of the pump sucker rod as well as the column of fluid pumped, thus reducing useless load on the 15 pumping engine.

Other objects and advantages will present themselves as the nature of the invention is better understood, reference being had to the accompanying drawings, in which there 20 is illustrated a simple and satisfactory exemplification of the improvement reduced to practice, it being understood, however, that the nature of the invention is such as to render the same susceptible to various 25 changes in size, proportion and details of construction, all of such changes, however, falling within the scope of what is claimed.

In the drawings:

Figure 1 is a side elevation of the improvement.

Fig. 2 is a top plan view thereof.

Fig. 3 is a sectional view approximately on the line 3—3 of Fig. 2.

Fig. 4 is a sectional view approximately 35 on the line 4—4 of Fig. 1.

The base 10 for my improved pumping jack is preferably constructed of oak timbers. On the side members of the base is secured the frame 11 for the walking beam.

40 The frame 11 includes a member having spaced legs 12 the lower portions of which being offset or arranged at an outward angle to provide feet 13, and these feet are secured to the base. The side members or legs 12

45 of the frame 10 are braced by angularly arranged members 14 that are secured to the said legs and to the base. The upper and straight portion of the frame 11 is bifurcated or is provided with spaced ears 15—15,

50 and between these ears is arranged the walking beam 16. The walking beam, to one side of the center thereof is provided with a plurality of spaced openings 17, and the ears 15 are provided with alining openings.

Passing through the last mentioned openings 55 and through one of the openings 17 in the walking beam is a pivot bolt 18 that has its threaded portion engaged by a nut 19. The end of the walking beam, farthest away from the pivot 18 has removably suspended 60 thereon a counter-balancing weight 20. The walking beam, adjacent its opposite end has connected thereto a pitman 21, and the lower end of this pitman is pivotally connected, as at 23 to the saddle casting 24. The casting 24 has connected therewith a laterally extending axle 25 which finds bearings in suitable block members 26 that are secured to the side members of the base and that preferably have their outer surfaces contact- 70 ing with the legs 12 of the frame 11. The saddle casting 24 has its inner end provided with or connected to an angle arm 27 which extends upwardly and which is provided, adjacent its outer end with any de- 75 sired number of spaced transverse openings 28, any of the said openings designed to receive the shackle rod or cable 29 that is connected with the engine or with the mechanism for actuating the pump. 80

Outward of the pivotal connection of the pitman 21 with the walking beam 16, the said walking beam is provided with a depending link 30, and to this link is connected a rod 31 which in turn is connected to the 85 piston or pump sucker rod in the well casing.

The weight 20 on the walking beam serves to equalize the dead weight of pump sucker rods as well as the column of fluid pumped, and consequently reduces useless load on the 90 pumping engine. The improvement permits of the employment of a smaller engine that is usually employed in such work as well as considerably lighter shackle rods or cables in the operation thereof. The counter-bal- 95 ance is adjusted in two ways, first by the weight, second by the distance from the fulcrum or pivot 18 which connects the walking beam to the frame. No gearing is employed in the construction which consequently 100 greatly reduces the cost thereof. The shackle rod or cable 31 is adjustably connected to the angle arm, which in connection with the saddle casting provides a bell crank lever so that the stroke of the pump can be 105 changed easily, according to the capacity of the well which enables the engine to operate continuously under steady load and

which also balances the load on the engine when a single engine operates a number of wells.

Having thus described the invention, what is claimed as new, is:—

In a pumping jack, a base, a frame secured thereto and arising therefrom, said frame including spaced legs, brace members between the legs and base, spaced ears on the outer end of the frame, a walking beam having spaced openings therethrough disposed nearer one end thereof than the other, a pivot member passing through the ears and through one of the said openings, a counter-balancing weight on the walking beam at the end thereof farthest from the pivot, a link pivotally secured to the walk-

ing beam adjacent to the opposite end thereof, a saddle casting having a lateral axle connected to the link, bearings on the base 20 for said axle contacting with the arms of the frame, an angle arm secured to the free end of the saddle casting, said arm having spaced transverse openings therethrough designed to receive in any one thereof a shackle 25 rod or cable which is connected to the operating engine for the jack, a link on the end of the walking beam outward of the first mentioned link, a rod connected therewith, said rod being connected with the 30 sucker rod of a pump.

In testimony whereof I affix my signature.

HENRY T. SCOTT.
